UNITED STATES PATENT OFFICE.

RAYMOND F. HANCOCK, OF MARION, INDIANA, ASSIGNEE OF ONE-HALF TO JAMES BOYCE, OF GIBSON, MICHIGAN, AND ONE-HALF TO HARRY F. ANDERSON, OF MARION, INDIANA.

GLASS ROLLING AND PRESSING MACHINE.

Application filed July 6, 1921. Serial No. 482,755.

To all whom it may concern:

Be it known that I, RAYMOND F. HANCOCK, a citizen of the United States, residing at Marion, in the county of Grant and 5 State of Indiana, have invented certain new and useful Improvements in Glass Rolling and Pressing Machines; and I do declare the following to be a full, clear, and exact 10 description of the invention, such as will enable others skilled in the art to which it appertains to make and use the same.

This invention relates to a machine for rolling molten glass into a sheet and pressing figures into the glass, and one object of 15 the invention is to provide a machine in which the molten glass can be easily rolled into a flat sheet and during the rolling process, a figure formed by a raised portion upon a roller forcing the glass down into a 20 corresponding recess in the table upon which the molten glass is placed.

Another object of the invention is to so construct the table and roller that a sleeve carrying the raised figure may be removably mounted upon the roller and a plate carrying the corresponding recess removably carried by the table.

Another object of the invention is to so construct this table that the rolled plate of 30 glass may be lifted from the table after the roller has passed over the glass thus making it easy to remove the pressed plate of glass from the table.

Another object of the invention is to provide 35 a machine of the character described which will be simple in construction and easy to operate and which will consist of a comparatively few number of parts easy to assemble and not liable to move out of the 40 proper position.

This invention is illustrated in the accompanying drawings, wherein:

Figure 1 is a top plan view of the improved machine.

Figure 2 is a view showing the improved machine in side elevation.

Figure 3 is a transverse sectional view through the improved machine.

Figure 4 is a longitudinal sectional view 50 through the machine taken on the line 4-4 of Fig. 3.

This machine is provided with a table having a top or platform 1 supported by legs or standards 2. A pocket 3 is formed

in the top 1 to carry a plate 4 upon which 55 will be formed a letter or other character 5 for forcing glass into a corresponding recess 6 formed in the sleeve 7 of the roller 8. It should be noted that the plate 4 tapers 60 downwardly as shown in Figs. 3 and 4 and that the pocket 3 is of a corresponding shape so that the plate may be easily set into this pocket. Fastening screws 9 are provided as shown in Figs. 3 and 4 so that this 65 plate 4 can be securely but releasably held in place. The sleeve 7 is held in the proper position upon the roller 8 by fasteners 10 which are in the form of machine screws as shown in Fig. 3. It will thus be seen that a 70 number of corresponding plates and sleeves can be provided and the proper sleeve and plate put in place according to the letter, figure or other character which it is desired to form in the plate of glass.

The roller 8 is carried by a shaft 11 which 75 extends beyond the ends of the tubular hub 12 of the roller and has its end portions resting upon the tracks 13 which are upon and extend longitudinally of the table top 1. The table 1 further carries rack bars 14 for 80 engagement by gears or pinions 15 mounted upon the end portions of the shaft 11. It will thus be seen that when the shaft 11 is turned through the medium of the turning handle 16, the roller will be moved longitudinally of the table and will be retained in the proper position and further caused to rotate properly so that the raised character 85 of the plate 4 will always fit properly into the depression or seat 6 formed in the 90 sleeve 7.

When this device is in use, the proper plate 4 and sleeve 7 are put in place and the roller will be positioned adjacent one end 95 of the table. The molten glass is then poured onto the table in front of the roller and the roller is caused to move longitudinally of the table through turning of the shaft by means of the handle 16. As the roller moves along the table, the molten glass will be rolled into a sheet of the thickness corresponding to the distance between the top of the table and the surface of the roller. When the roller reaches the position shown in Fig. 4, the raised character 6 will 100 force the molten glass up into the corresponding recess 5 of the plate 4 thus providing a character having the same thickness 105

as the remainder of the plate and appearing upon one side of the plate as a depression and upon the second side of the sheet of glass as a raised character. After the sheet 5 or plate of glass has been formed and has cooled the proper amount, it will be lifted from the table and another can then be formed. If the second sheet of glass is to have the same character, no adjustment is 10 necessary but if a different character is to be formed, the plate and sleeve will be removed and the proper ones put in place.

In order to lift the plate of glass from the table, there has been provided strips 17 15 which are embedded in the table top. These strips are engaged by a yoke 18 which has its arms extending through openings 19 formed in the table top. An actuating lever or treadle 20 is pivotally mounted beneath 20 the table by means of a hanger bracket 21 and has its inner end portion connected with the yoke by means of a link 22. By pressing upon the treadle 20, the yoke will be 25 forced upwardly through the table top thus elevating the strips 17 and lifting the plate or sheet of glass off of the table so that it can be easily removed from the table. In the present illustration the plate has been 30 provided with a raised character and the sleeve provided with a corresponding recess but it is obvious that this arrangement

can be reversed and the sleeve provided with the raised character and a corresponding recess formed in the plate.

35

I claim:

1. A glass machine comprising a table, a roller mounted for rolling movement above said table, strips embedded in said table and extending longitudinally thereof, a U-shaped 40 yoke beneath said table and extending transversely thereof and having arms extending up through openings in the table and connected with said strips, and means for moving the yoke upwardly to project 45 its arm upwardly through the table and move said strips upwardly to lift a sheet of glass off of said table.

2. A machine of the character described comprising a table, means for pressing material into a sheet upon said table, strips embedded in said table, a yoke having arms extending upwardly through openings in said table and connected with said strips, a treadle pivotally mounted beneath said table, and a link connecting said treadle with said yoke for moving the yoke and strips upwardly to lift a sheet of pressed material from the table when pressure is applied to said treadle.

50

In testimony whereof I have hereunto set my hand.
